Term of patent 14 years

(Cl. D52—2)

Fig. 1.

Fig. 2.

Figure 1 is a perspective view of a tissue dispenser showing my new design; and

Figure 2 is a top plan view thereof.

The side and end of the tissue dispenser not shown are substantially the same as the side and end shown in Figure 1 of the drawings.

The characteristic features of my new design for the tissue dispenser disclosed reside in the oval pattern portions substantially in the relationship shown.

I claim:

The ornamental design for a tissue dispenser, substantially as shown and described.
